[57] CLAIM

The ornamental design for a combined collapsible dispenser and cap, as shown and described.

DESCRIPTION

FIG. 1 is a front elevational view of a combined collapsible dispenser and cap showing our new design;

FIG. 2 is a front elevational view thereof, shown with the cap removed for clarity of illustration;

FIG. 3 is a side elevational view thereof;

FIG. 4 is an enlarged fragmentary side elevational view thereof;

FIG. 5 is an enlarged fragmentary front elevational view thereof;

FIG. 6 is a top plan view thereof;

FIG. 7 is a bottom plan view thereof; and

FIG. 8 is a top plan view shown with the cap portion in place.

FIG. 2**FIG. 1****FIG. 3****FIG. 4****FIG. 5****FIG. 6****FIG. 7****FIG. 8**
